UNITED STATES PATENT OFFICE.

VICTOR D. PHELPS, OF WHITING, INDIANA, AND LUCY MOLYNEAUX, OF WOODLAND, ILLINOIS.

SCRUBBING CAR.

1,402,649.

Specification of Letters Patent. Patented Jan. 3, 1922.

Application filed May 9, 1921. Serial No. 468,115.

To all whom it may concern:

Be it known that we, VICTOR D. PHELPS and LUCY MOLYNEAUX, citizens of the United States, residing at Whiting and Woodland, in the respective counties of Lake and Iroquois and States of Indiana and Illinois, have invented new and useful Improvements in Scrubbing Cars, of which the following is a specification.

10 This invention relates to a scrubbing device and has for its primary object the provision of a scrubbing car whereby the scrubbing of floors may be accomplished in a relatively easy manner.

15 An object of the invention is the construction of a car that may be moved across the floor with very little effort and which will not mar the floor.

A feature of the invention is the padding of the car so as to relieve the scrubber of excessive strains.

Besides the above our invention is distinguished in the novel manner of constructing and associating the various parts so that 25 they may be quickly disconnected.

With these and other objects in view the invention will be better understood from the following detailed description taken in connection with the accompanying drawing 30 wherein:

Fig. 1 is a top plan view of the car.

Fig. 2 is a side elevation.

Fig. 3 is a cross sectional view.

The remaining figures are detail views.

35 Again referring to the drawings illustrating one of the many constructions of our invention the numeral 1 designates the base supported by the casters 2 so as to be easily moved over the floor and prevent marring 40 of the floor. This base is provided with openings 3 that detachably receive the pins 4 extending from the frame 5. The frame 5 is provided with an upstanding wall 6 on three sides, and adjacent the bottom of the 45 frame is provided a cleat 7 supporting the

cushion 8. This cushion consists of a body portion 9 and a padding 10 upon which the knees of the operator rest.

It will be noted that the base is provided with recesses 11 slidably receiving the cross bars 12 of a rack 13. To complete the rack we provide end supports 14 which are of a size to rest directly against the floor so that a pail of water may be supported on the rack without the same being subject to excessive strains. It will also be noted that the rack may be extended from one side to another so that a pail of water may be arranged on either side. To complete the structure we provide a tray 15 extending forwardly of the base to support soap, wash rags or any other articles.

From the foregoing description taken in connection with the accompanying drawing it will be seen that we provide a device that will greatly relieve the user of excessive strains and fatigue, and besides, will keep the clothes of the user in a dry condition, and further the floor is properly protected which is a great advantage.

It is, of course, to be understood that the invention may be constructed in various other manners and the parts associated in different relations and, therefore, we do not desire to be limited in any manner except as set forth in the claim hereunto appended.

Having thus described our invention what we claim is:

A scrubbing car comprising a base provided with openings, a frame having pins 80 that are detachably mounted in the openings, casters secured to the base, a tray secured to the base, a rack adjustably supported by the base, and a cushion removably supported by the frame.

In testimony whereof we affix our signatures.

VICTOR D. PHELPS.
LUCY MOLYNEAUX.
